UNITED STATES PATENT OFFICE.

EDWIN HILL, OF NORWICH, CONNECTICUT.

BILLIARD-CUE-TIP CHALKER.

Application filed October 22, 1921. Serial No. 509,595.

To all whom it may concern:

Be it known that I, EDWIN HILL, a citizen of the United States, residing at Norwich, in the county of New London and State of Connecticut, have invented certain new and useful Improvements in Billiard-Cue-Tip Chalkers, of which the following is a specification.

This invention relates to holders for chalk used in chalking the tips of cues used in playing billiards or pool.

It is customary for the player in games of pool and billiards to frequently apply chalk to the leather tip of his cue in order to prevent the same from slipping on the surface of the ball and to do this a block of chalk with a hemispherical depression therein is utilized the tip of the cue being placed within the depression and the block 20 of chalk rotated to apply the chalk to the tip.

The object of this invention is to provide a holder for a block of chalk of this character which may be secured to any suitable support and is so constructed that the block may be rotated for chalking the cue without dust from the chalk getting on the hands of the player or onto his clothing, and which prevents the player from putting 30 the chalk in his pocket and carrying it off.

Another object of the invention is to provide a device of this character which has no springs or frangible parts liable to be broken and which will present an attractive 35 appearance when attached to a pool or billiard table or to any other suitable support.

Another object is to provide a holder of this character having a chalk container rotatable within the supporting member and 40 which may be readily removed from said member for applying additional blocks of chalk when necessary, a suitable key for holding the rotary member against turning being provided when the container is to be removed.

With these and other objects in view, the invention consists in certain novel features of construction as hereinafter shown, described and claimed.

50 In the accompanying drawings:—

Figure 1 represents a perspective view of this improved chalk holder shown applied.

Fig. 2 is a vertical section therof, and

55 Fig. 3 is a side elevation of the key used in connection with the device.

The chalker constituting this invention comprises a bracket 1 having an apertured attaching flange 2 at one end thereof and a cylindrical guide or casing 3 at its other end said guide extending laterally from said end and projecting on opposite sides of said bracket as is shown clearly in Fig. 2 of the drawings. The casing 3 has one end chamfered out on its inner face as shown at 4 with a shoulder 5 formed at the inner end of said chamfered portion and which is designed for a purpose presently to be described. This casing or cylindrical guide 3 is adapted to be secured to any convenient support by means of the bracket 1 and has 60 mounted therein a tubular member 6 of a length greater than the casing 3 and adapted to be rotatably mounted therein. This tube 6 is provided on its outer face near the closed end thereof with an annular bead 7 65 which forms a stop or abutment for one end of the casing 3 to limit the insertion of the tube within said casing as is shown clearly in Figs. 1 and 2. The open end of the tube 6 is threaded exteriorly as shown at 80 8 for a purpose presently to be described. A chalk cup or chamber 10 is formed at the open end of the tube 6 by means of a transverse partition 11 spaced inwardly from said open end a distance corresponding 85 to the size of the ordinary chalk block B used in connection with devices of this character. An inwardly struck bead 12 forms a support for the partition 11 as is shown clearly in Fig. 2. 90

The outer end of the chalk cup or chamber 10 is closed by a cap-like closure 13 the body portion or flange 14 of which is internally threaded for engagement with the threaded portion 8 of the tube 6. This 95 cap-like closure 13 has a central opening 15 which registers with the depression D in the chalk block B and is designed for the insertion of the cue tips to be chalked. This cap 13 is also provided in its outer face 100 with a pair of diametrically opposite apertures 16 which are designed to receive the tongues 18 of a key 17 which is designed to hold the cap 13 against turning when the tube 6 is to be unscrewed therefrom which 105 is necessary when the chalk block is to be renewed.

The edge of the flange 14 is designed to engage the shoulder 5 of the casing 3 and operates as a stop to prevent the withdrawal 110

of the casing or tube 6 in one direction the bead 7 limiting its movement in the opposite direction.

From the above description it will be obvious that the cap 13 is first inserted in the chamfered end of the casing 3 and then the tube 6 having the chalk block B mounted in the chamber 10 thereof is inserted in said casing 3 and rotated to connect it with the flanged portion of the cap. When the parts are so arranged the device is ready for use and the tube 6 may be rotated within the casing 3 for chalking the cue tip in a manner which will be obvious.

When it is desired to renew the chalk block the key 17 has the prongs 18 thereof inserted in the aperture 16 of the cap 13 and the casing 6 is rotated to unscrew it from said cap and permit its withdrawal from the casing 3, and after a new block has been supplied it is reinserted in the manner above set forth. It will thus be seen that the chalk cannot be surreptitiously removed, since the one removing it must have access to the key 17 to hold the closure 13 while the tube is being unscrewed as otherwise the closure will turn with the tube.

From the above description it will be obvious that this device is composed of comparatively few parts and has no springs or other fragile parts liable to become broken and therefore will last indefinitely and will adequately protect the player's hands and clothing against chalk dust.

The preferred embodiment of the invention is disclosed in the drawings and set forth in the specification, but it will be understood that any modifications within the scope of the claimed invention may be made in the construction without departing from the principle of the invention or sacrificing any of its advantages.

I claim:—

1. A billiard cue chalker comprising a cylindrical guide having a bracket for attachment to a support, a tube slidable and rotatable in said guide and provided at one end with a chalk chamber, a closure for said chamber rotatable in and held against longitudinal movement with respect to said guide, said closure and guide having cooperating inter-engaging means to prevent the withdrawal of the tube in one direction.

2. A billiard cue chalker comprising a cylindrical guide having a bracket for at-

achment to a support, a tube slidable and rotatable in said guide and provided at one end with a chalk chamber, a closure for said chamber rotatable in said guide, said closure and guide having cooperating inter-engaging means to prevent the lengthwise movement and withdrawal of the tube in one direction, and a bead on said tube to engage the other end of the guide to limit its withdrawal in the opposite direction. 60 65

3. A billiard cue chalker comprising a cylindrical guide having a bracket extending radially therefrom for attachment to a support, one end of said guide being chamfered out on its inner face to form a seat, 70 a closure member for the end of said guide flanged to fit and rotate in said seat, said closure being centrally apertured, a tube slidable and rotatable in said guide and provided at one end with a chalk chamber 75 to be closed by said closure and cooperating means on said tube and guide for limiting the insertion of the tube and to prevent its withdrawal in one direction, the closure and said tube having threaded engagement and 80 the closure operating to prevent the withdrawal of the tube in the opposite direction.

4. A billiard cue chalker comprising a cylindrical guide having an attaching bracket extending radially therefrom intermediate the ends thereof, one end of said guide being chamfered out on its inner face to form a seat with a shoulder at its inner end, an annular flanged closure for said end with the flange rotatably mounted on said seat and with its edge abutting said shoulder, said closure being centrally apertured, a tube slidable and rotatable in said guide and having a horizontal partition therein to form 90 a chalk chamber at one end said chamber carrying end being externally threaded and said closure flange being correspondingly threaded to engage said tube whereby the closure operates to close the end of said tube and also to prevent its withdrawal from the guide in one direction, and a bead on said tube near its other end and located in position to engage the other end of the guide to prevent the withdrawal of the tube in 95 the opposite direction. 100 105

In testimony whereof, I affix my signature hereto.

EDWIN HILL.
